UNITED STATES PATENT OFFICE.

LEE E. LOGAN, OF MILWAUKEE, WISCONSIN.

CAR SEAL.

Application filed February 5, 1926. Serial No. 86,209.

This invention relates to car seals.

Objects of this invention are to provide a seal for cars which is so constructed that it may be readily fastened in position to seal the car, and which may not be thereafter opened without breaking the parts of the seal in a conspicuous manner.

Further objects are to provide a seal in which a main member provided with an integral strap cooperates with an auxiliary member in such a manner that the initially free end of the strap is interlocked with the auxiliary member in a very secure manner, and that its interlocking is reinforced by the inherent characteristics of the device.

Embodiments of the invention are shown in the accompanying drawings, in which:

Figure 1 is a view of the main member and the integral strap projecting therefrom. Figure 2 is a view of the reverse side from that shown in Figure 1.

Figure 2^a is a view showing the free end of the strap in engagement with the auxiliary member with the main member removed.

Figure 3 is a view showing the parts coupled, or in other words, showing the seal closed.

Figure 4 is a view corresponding to Figure 3 taken from the opposite side thereof.

Figure 5 is a view of the inner portion of the auxiliary member.

Figure 6 is an enlarged sectional view on the line 6-6 of Figure 4.

Figure 7 is an enlarged sectional view on the line 7-7 of Figure 4.

Figure 8 is a view of a modified form showing the parts opened out.

Figure 9 is a sectional view showing the form illustrated in Figure 8, with the free end of the strap being inserted into the seal.

Figure 10 is a view corresponding to Figure 9 showing the completion of the interlocking or sealing operation.

Figure 11 is a view corresponding to Figure 8 showing a modified form of construction.

Referring to the drawings, it will be seen that a main member 1 is provided with an integral outwardly projecting strap 2. This main member 1 is preferably elliptical, although it may be made in other shapes,—for instance, circular or polygonal. The main member 1 is provided with a depressed channel 3 and with a marginal upwardly extending flange 4. This flange is cut away at the

point where the strap 2 joins the body portion 1 and is also cut away as indicated at 5, on the opposite side thereof.

The main member 1, as may be seen from Figure 2, is provided with a pair of projecting ribs 7 arranged in spaced relation between which a tongue 8 is inwardly folded. It is to be noted from reference to Figures 1 and 2, that a small projection formed by depressing a portion of the main member, is provided adjacent the tongue. This depression is indicated by the reference character 9 and prevents the tongue 8 from being flattened against the body of the main member.

The integral strap 2, which projects from the main member, is provided with an enlargement, such as the disc-like portion 10 adjacent its free end. It is further provided with a slot or aperture 11 beyond the enlargement 10.

The auxiliary member comprises a body portion 12, as most clearly shown in Figure 5, which is also equipped with an upwardly extending marginal flange 13 and with a pair of projecting ribs 14 arranged in spaced relation to each other. A tongue 16 is formed integral with the body portion and is preferably provided with a pair of outwardly projecting ears 17. It is to be noted that this tongue 16 is narrower than the tongue 8 and also than the strap 2. This auxiliary member is provided with a projecting portion 18 corresponding to the portion 9 of the main member, and such projecting portion holds the tongue 16 spaced from the body portion 12 of the auxiliary member, and prevents it being flattened against such member.

In the device as it appears when completed the auxiliary member and the main member are beaded together as described. In using this device the free end of the strap 2 is inserted between the members 100 and pushed forwardly until the notch 11 passes the tongue 16. Thereafter it is drawn outwardly thus causing the interlocking of the tongue 16 with the notch 11. The relative position of the parts are indicated in Figures 6 and 7.

It is to be noted that the projecting ribs 7 and 14 form spacing members for the strap 2 and for the tongues 8 and 16.

It is to be noted that the ears 17 of the tongue 16 serve as a stop for the strap 2 after the tongue 16 has been passed through

the aperture 11. Further, these ears must necessarily be torn before the strap can be pulled out, and also the body of the tongue 16 must also be broken, or else the strap 6 5 must be severed. In addition to this, the enlargement 10 being positioned on the outer side of the sealed members prevents reinsertion of the strap 2 in case it is broken.

Referring to Figures 8, 9, and 10, it will 10 be seen that the seal comprises a main member 19 which is integrally joined by means of a tongue 20 to an auxiliary member 21. The main member 19 has a strap 22 projecting therefrom. This strap corresponds to 15 the strap 2 of the first form and is provided with an enlargement 23 and with a notch 24.

The auxiliary member 21 is provided with an inwardly turned portion 25 which is itself equipped with an upwardly struck 20 tongue 26 and with an inwardly folded terminal flange or member 27 positioned below the point of the tongue.

The main member 19 is provided with a recess 28 adapted to accommodate the tongue 25 26 and with a depressed rib 29 which fits back of the flange 27 as shown in Figures 9 and 10.

The members are beaded together as 30 shown in Figures 9 and 10 in a manner similar to that previously described.

In using this form of device, the free end of the strap is passed inwardly between the members as shown in Figure 9. The strap is pushed inwardly until the notch 24 is engaged by the tongue 26.

It is to be noted that the depressed portion 29 guides the end of the strap downwardly and facilitates engagement with the tongue 26. Thereafter the strap is pulled 40 forwardly a slight distance thus placing the parts in the position shown in Figure 10.

It will be seen that the initially free end of the strap is securely engaged and cannot be removed without breaking the parts. 45 For example, if it is attempted to dislodge the strap by shoving it inwardly when the parts are in the position shown in Figure

10, it is apparent that the strap will pass beneath the inwardly turned member 27 and cannot be disengaged from the tongue. 50 Consequently the device cannot be opened up without breaking the seal.

The form of invention illustrated in Figure 11 is identical with that illustrated in Figure 8 except that the main member 19' and the auxiliary 21' are formed in separate pieces. Otherwise the invention is identical with that described above.

It will be seen that a very simple seal has been provided, which is highly effective in 60 operation, which may be cheaply manufactured, and which may be readily applied.

Although the invention has been described in considerable detail, such description is intended as illustrative rather than limiting 65 as the invention may be variously embodied and as the scope of such invention is to be determined as claimed.

I claim:

A car seal comprising a hollow disc-like member having a strap extending therefrom and having a marginal flange provided with a notch through which the free end of said strap may be passed, such free end having an aperture formed therein, said disc-like portion having an internally located prong pointing away from said strap and having an internally located shield reversely turned and pointing toward said strap and having its edge located below said prong, said disc-like member having one of its walls adjacent the free end of said prong curved and extending downwardly rearwardly of said prong to provide a guiding cam surface for guiding said strap into engagement with 85 said prong, said strap after engaging said prong having its extreme free end located below said shield.

In testimony that I claim the foregoing I have hereunto set my hand at Milwaukee, 90 in the county of Milwaukee and State of Wisconsin.

LEE E. LOGAN.
